[57] CLAIM

The ornamental design of an adjustable lamp body for modular lighting system, as shown and described.

DESCRIPTION

FIG. 1 is a front elevational view of my design, the rear elevational view thereof being identical;

FIG. 2 is a side elevational view of my design as viewed from the right hand side of FIG. 1, the left hand side elevational view being identical;

FIG. 3 is a top plan view of my design, the bottom being identical thereto; and,

FIG. 4 is a front perspective view thereof.

FIG.1

FIG.2

FIG.3

FIG.4
